UNITED STATES PATENT OFFICE.

JOHN C. GABEL, JR., OF ONARGA, ILLINOIS.

DESIGN FOR A HINGE FOR DOOR-HANGERS.

SPECIFICATION forming part of Design No. 31,592, dated October 3, 1899.

Application filed August 29, 1899. Serial No. 728,915. Term of patent 14 years.

To all whom it may concern:

Be it known that I, JOHN C. GABEL, Jr., of Onarga, in the county of Iroquois and State of Illinois, have invented and produced a new and original Design for a Hinge for Door-Hangers, of which the following is a full, clear, and exact description.

Reference is to be had to the accompanying drawings, forming a part of this specification, in which—

Figure 1 is a face view of a hinge, showing my design; and Fig. 2 is an edge view of the hinge.

The leading feature of my design consists of a hinge for door-hangers having an upper portion with a convexed top and downwardly-

flaring concaved sides. In the central vertical line of said upper portion is located an aperture, at the sides of which are arranged spherically-rounded ring-shaped projections. ²⁰ The central portion of the hinge has a horizontal top, vertical side edges, and a curved bottom edge, and the lower section also has three through-apertures arranged as shown in Fig. 1. ²⁵

I claim—

The design for a hinge for door-hangers, herein shown and described.

JOHN C. GABEL, JR.
